COMBINED JEWELRY DISPLAY AND STORAGE BOX

David B. Seaman, New York, N.Y., assignor to Off The Cuff Accessories, Inc., New York, N.Y., a corporation of New York

Filed June 9, 1969, Ser. No. 17,595

Term of patent 7 years

Int. Cl. D9—04

U.S. Cl. D9—189

FIG. 1 is a front perspective view of a combined jewelry display and storage box showing my new design; FIG. 2 is a rear perspective view thereof;

FIG. 3 is an elevation thereof in an open condition as seen from the left of FIG. 1; and

FIG. 4 is a front perspective view thereof in an open condition.

The bottom of the design is substantially plain and unornamented.

The characteristic feature of my design for the combined jewelry display and storage box disclosed resides in the intersecting circular pockets within the interior cover and interior base of the box in the position and relation shown.

I claim:

The ornamental design for a combined jewelry display and storage box, as shown and described.
